UNITED STATES PATENT OFFICE

135,412

DESIGN FOR A CABINET FOR A VENDING MACHINE

John F. Meyer, Chicago, Ill., assignor to The Exhibit Supply Company, Chicago, Ill., a corporation of Illinois

Application November 23, 1942, Serial No. 108,843

Term of patent 7 years

To all whom it may concern:

Be it known that I, John F. Meyer, a citizen of the United States and a resident of Chicago, in the county of Cook and State of Illinois, have invented a new, original, and ornamental Design for a Cabinet for a Vending Machine, of which the following is a specification, reference being had to the accompanying drawing, forming a part thereof, and in which:

Fig. 1 is a perspective view of a cabinet for a vending machine showing my new design;

Fig. 2 is an elevational view of the same as seen from line 2—2 in Fig. 1; and

Fig. 3 is a top plan view of the same.

I claim:

The ornamental design for a cabinet for a vending machine, as shown.

JOHN F. MEYER.
